UNITED STATES PATENT OFFICE.

FREDERIC AUMONIER, OF LONDON, ENGLAND.

DESIGN FOR WALL-PAPER.

SPECIFICATION forming part of Design No. 23,004, dated January 9, 1894.

Application filed December 13, 1893. Serial No. 493,610. Term of patent 3½ years. Registered in England March 3, 1893, No. 208,517.

To all whom it may concern:

Be it known that I, FREDERIC AUMONIER, (trading as Wm. WOOLLAMS & Co.,) a subject of the Queen of Great Britain, and a resident of 110 High street, near Manchester Square, London, England, have invented a new and original Design for Wall-Paper, (registered in Great Britain on the 3d day of March, 1893, No. 208,517,) of which the following is a specification.

This design for wall paper as represented by the accompanying drawing consists of frieze, filling and dado. The frieze is a kind of balcony with somewhat square ornamental columns having scrolled canopies, vases and urns of flowers on ornamental stands arranged between the columns alternately, the intermediate being similarly arranged but with a basket of flowers standing from a vase the flowers being surmounted by festoons supported from corbels and a tassel hanging therefrom. The filling consists of wavy acanthus like branches the part between the bulged out portions of said branches being

filled with an orchid like flower throwing from its upper sides other flowers, the lower portion having sprigs spread outwardly with a flower at the top of each, a cactus head merging from leaves filling the interstice between the sprigs and the narrow scroll of acanthus leaves. The dado has a beading of medallions and festooned like groups of flowers the points of which approach an ornamental scroll surmounted by a bowed knotted ribbon. Below the beading are imaginary scrolls and leaves associated with daisy flower like fillings some of which appear in front of the leaves.

I claim—

The design for wall paper substantially as shown and described.

The 10th day of March, 1893.

FREDERIC AUMONIER.
